SPRAY GUN

Burr W. Mantle, Pittsford, N. Y., assignor to
 American Brake Shoe Company, New York,
 N. Y., a corporation of Delaware

Application October 6, 1949, Serial No. 119,850

3 Claims. (Cl. 299—143)

1

This invention relates to spraying devices and more particularly to spray guns of the type adapted to spray two solutions simultaneously.

In certain commercial processes and the like, such as, for example, in the silvering of mirrors, it has been found desirable to simultaneously spray two solutions on a surface to be coated. Various types of spray guns and other similar spraying devices have heretofore been developed for so spraying two solutions. However, the spraying devices heretofore developed for this purpose have had several inherent disadvantages such as, for example, being complicated in construction or operation; being heavy in weight, large in size, and, therefore, difficult to handle; or being impractical and inefficient in operation.

It is a primary object of my invention to overcome these disadvantages and to afford a novel spray gun of the aforementioned type which is constructed, and operable, in a novel and expeditious manner.

Another object of my invention is to enable a spray gun to be constructed by which two coating solutions may be simultaneously sprayed at the desired rate of consumption in a novel and expeditious manner.

A further object of my invention is to so construct a spray gun of the aforementioned type that the parts thereof, and the other mechanism used in conjunction therewith during a spraying operation, may be constituted and arranged in a novel and expeditious manner whereby the spray gun is easily used and is practical and efficient in operation.

Yet another object of my invention is to construct a spray gun of the aforementioned type in such a manner that the gun may be quickly and readily assembled and disassembled for the purpose of cleaning, repairing, or replacing the various parts thereof.

Many solutions used in processes such as silvering mirrors, and the like, employ solutions which are highly corrosive, and it is an important object of my invention to construct a novel spray gun in such a manner that, when such solutions are used therein, the corrosive effect of the solutions on the gun is minimized.

An object ancillary to the foregoing is to construct a novel spray gun of the aforementioned type in such a manner that corrosive materials fed therethrough contact a minimum of metal and pass through only short, straight passageways that may be readily cleaned.

Another object of my invention is to provide a spray gun embodying a novel nozzle head con-

stituted and arranged in a novel and expeditious manner wherein compressed air may be fed in a novel manner from a common passageway in the body of the gun simultaneously into two nozzles to thereby afford novel means for feeding aspirating air into and through the two nozzles.

During the operation of spray guns of the type to which my invention relates, the guns are customarily connected to the source of fluid supply by flexible rubber hoses and the like, and the proper positioning of the latter so that they do not interfere with the manipulation of the gun during a spraying operation has been a problem. In this connection, it is a further object of my invention to provide a spray gun embodying novel clamping means for supporting the fluid supply hoses in a novel and expeditious manner on the gun.

Another object is to construct a spray gun embodying novel clamping means on the rear end portion of the body of the gun which is adapted to hold fluid supply hoses and the like in close-fitting parallel relation to the body of the gun, and which may be quickly and easily attached to, and released from, such hoses in a novel and expeditious manner.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

40 In the drawings:

Fig. 1 is a perspective view of a spray gun embodying the principles of my invention;

Fig. 2 is a perspective view of a spray gun showing the gun connected to apparatus with 45 which it may be used;

Fig. 3 is a longitudinal sectional view of the gun shown in Fig. 1;

Fig. 4 is a front elevational view of the nozzle head embodied in the gun shown in Figs. 1 and 3;

50 Fig. 5 is a detail sectional view taken substantially along the line 5—5 in Fig. 4;

Fig. 6 is a detail sectional view taken substantially along the line 6—6 in Fig. 3; and

Fig. 6-A is a detail sectional view similar to

Fig. 6 but showing the parts disposed in a different position of operation.

The gun 20, shown in Figs. 1 to 6, inclusive, of the accompanying drawings to illustrate a preferred embodiment of my invention, is especially well adapted for simultaneously spraying two solutions on a single surface, such as, for example, spraying a silvering solution and a precipitating solution simultaneously onto the back surface of a mirror. The gun embodies a body 22 having a handle 24 projecting downwardly from the rear end portion thereof and a nozzle head 26 attached to the front end thereof. The nozzle head 26 comprises two nozzles 28 and 29, mounted in a nozzle plate 31, Figs. 4 and 5, each of the nozzles 28 and 29 comprises a nozzle cap 28a and 29a, and a nozzle body 28b and 29b, respectively. The nozzle head 26 is mounted on the front end portion of the body 22 of the gun 20 and is secured thereto by a screw 33 and a bolt 34, the screw 33 extending through the upper end portion of the nozzle plate 31, as viewed in Fig. 3, and being in threaded engagement with the body 22, and the bolt 34 extending through a flange 35 depending from the front end portion of the body 22, and being disposed in threaded engagement with the nozzle plate 31 in an opening 37 formed in the lower end portion thereof.

Air enters the gun 20 through a passage 40 in the handle 24 and flows through the handle 24, the body 22, and out through the nozzle head 26, the aspirating effect of the air passing through the nozzles 28 and 29 being effective to cause solutions to be drawn from containers such as bottles A and B, Fig. 2, into the fluid nozzle bodies 28b and 29b, respectively, and discharged from the air caps or nozzle caps 28a and 29a, as will be discussed in greater detail presently.

The outer end portion of the air passage 40, in the free end portion 42 of the handle 24, is tapped to provide threads into which a suitable threaded coupling member 46 may be screwed, Fig. 3, to attach an air hose or the like to the gun 20. The air passage 40 extends inwardly from the free end portion 42 of the handle and terminates at its inner end portion in an air inlet valve chamber 44.

A valve housing 48 having a longitudinally extending opening 49 and a plurality of transversely extending openings 51, Fig. 3, is screwed into the valve chamber 44 wherein it seats against a shoulder 53 formed therein. An air valve 54 having a recess 56 formed therein is mounted in the valve chamber 44 and is positioned to seat against a valve seat 58 formed on the inner end portion of the valve housing 48 adjacent to the inner mouth of the air passage 49. A push rod 60, having one end portion disposed in the recess 56 of the valve member 54, extends forwardly therefrom through a gland plug 61 screwed into the outer end portion of the valve housing 48. Gland packing 62 is positioned between the gland plug 61 and an inwardly extending collar 64 in the valve housing 48 to form a seal around the push rod 60 against the leakage of air from the longitudinal passage 49 in the valve housing 48. A collar 65, is loosely disposed on the push rod 60 and is urged against the packing 65 by a spring 67 mounted between the gland plug 61 and the collar 64, to thereby press the packing 65 against the collar 64. A compression spring 70 having one end portion engaged with the outer face of the air valve 54 and the other end portion thereof engaged with the inner surface of the handle 24 within a recess 72 formed therein, tends

to normally maintain the valve 54 in engagement with the valve seat 58 on the valve housing 48 and thereby seal the connection between the air chamber 44 and the longitudinal passage 49 in the valve housing 48. The outer, or front, end portion of the push rod 60, Fig. 3, engages a trigger 75 by which the push rod 60 and, therefore, the valve 54 may be moved inwardly to unseat the valve 54 from the valve seat 58 and thereby permit the flow of air from the air chamber 44 into the air passage 49 in the valve housing 48, the trigger 75 being pivotally mounted on the body 22 of the gun.

A second passageway 77, substantially parallel to the air passage 40, is formed in the handle 24 and extends substantially through the entire length thereof. The outer end portion of the passage 77 in the handle 24 is tapped to provide threads 78 into which a suitable plug 79 may be screwed to seal this outer end portion of the passageway 77 against the escape of air therefrom. At the point where the passageway 77 intersects the air chamber 44, the valve housing 48 is somewhat reduced in cross section so that a space 80 is provided between the valve housing 48 and the side walls of the air chamber 44 and the air passage 77, so that air flowing through the openings 51 may flow through the enlarged opening 80 around the valve housing 48 up into that portion of the air passage 77 thereabove.

From the valve housing 48 the air passage 77 extends on into the handle 24 and intersects with another bore 81 formed transversely through the handle 24. A threaded plug member 85, of the type shown in my co-pending application, Serial No. 734,819, filed March 14, 1947, now Patent No. 2,559,407, is screwed into the bore 81 and seats against a shoulder 86 formed therein to thereby seal the passageway 81 against the flow of air longitudinally therethrough. A hose clamp 90, Figs. 1, 3 and 6, is mounted on the outer end portion of the plug member 85 for supporting the hoses which may be connected to the nozzle head 26, as will be presently described in greater detail.

As is best seen in Figs. 1, 3 and 6, the hose clamp 90 comprises a hose clamp body 92, a retaining member 94 and a lever 96. The clamp body 92 has a channel-shaped recess 97 formed in the upper end portion thereof, and an opening 99 formed in the lower end portion thereof. The opening 99 is of such diameter that the plug member 85 fits relatively snugly therein but may be slipped freely therethrough. As is best seen in Fig. 3, when the hose clamp 90 is disposed in operative position on the plug 85 on the gun 20, the clamp body 92 is disposed in abutting relation to the rear face of the upper end portion of the handle 24. A collar 101 having a plug 103 screwed into the free end thereof is screwed onto the plug member 85 and abuts the outer face of the clamp body 92 to thereby retain the clamp body in operative position against the handle 24.

The retaining member 94 of the hose clamp 90, Figs. 1, 3 and 6, has recesses 105 formed in the opposite end portions thereof, and is adapted to be mounted in the channel 97 of the clamp body 92 with the opposite side portions of the channel 97 disposed in the respective recesses 105. The retaining member 94 may be formed of any suitable material, however, I prefer to construct this member of spring steel having such thickness that it is relatively resilient. When the clamp 90 is mounted in operative position on the gun 20, the lever 96 is attached to the gun by

suitable means such as a screw 107, Fig. 3, which extends therethrough and is threadedly engaged with the plug 109 mounted in the rear end portion of a passageway 111 which extends longitudinally through the body 22 of the gun 20. A suitable spacing member 113 is disposed between the lever 92 and the plug 109 to hold the lever 96 in alignment with the retaining member 94 and the clamp body 92.

From the foregoing, it will be seen that, with the retaining member 94 removed from the clamp 90, hoses such as, for example, hoses H1 and H2, Figs. 1 and 6, which may be connected to the nozzle head 26, may be extended rearwardly along the body 22 of the gun 20 and disposed in the channel 97 of the clamp body 92. The retaining member 94 may then be mounted on the clamp body 92 above the hoses H1 and H2, by inserting one end of the retaining member 94 into operative engagement with the corresponding side of the channel 97, and then pressing that end downwardly sufficiently to permit the other end of the retaining member 94 to be moved into position in engagement with the other side of the channel 97. After being so inserted in the channel 97, the retaining member may be released and will then rest relatively lightly on the hoses H1 and H2 in the substantially horizontal position shown in Fig. 6, the overhanging lips 97a and 97b being operable to retain the retaining member 94 in such position on the hoses. In this manner, the clamp 90 is effective to support the hoses H1 and H2 on the gun 20 in a novel and expeditious manner.

It will be seen that, when the retaining member is disposed on the hoses H1 and H2 in the position shown in Fig. 6, with the lower end of the lever 96 disposed above, or merely resting lightly on, the upper surface of the retaining member 94, the portions of the hoses H1 and H2 extending through the clamp 90 are open so that fluid may flow freely therethrough. However, the lever 96 is so disposed relative to the clamp body 92, that if it is desired to close the hoses H1 and H2, this may be accomplished by swinging the lever 96 into the vertical position shown in Fig. 6-A wherein it is effective to press the retaining member 94 downwardly so as to squeeze the hoses H1 and H2 between the retaining member and the lower face of the channel 97 with sufficient force to collapse the side walls of the hoses H1 and H2 and thereby close the passages therethrough.

Thus it will be seen that the clamp 90 affords an efficient and readily available means for the operator to control the flow of fluid through the hoses H1 and H2, the lever 96 being readily available to the operator at all times, even during an actual operation of the gun 20.

Also, it will be seen that if it is desired to remove the hoses H1 and H2 from the gun 20, they may be quickly and easily released from the clamp 90 by merely swinging the lever 96 around out of engagement with the retaining member 94, and removing the retaining member 94 from the clamp.

At the point where the passageway 11 intersects the bore 81 in the handle 24, the plug member 85 is reduced in cross section so that a space 81a is formed between the plug member 85, the side walls of the bore 81, and the air passage 11, so that air may pass through the space 81a from that portion of the passageway 11 on one side of the plug member 85 to that portion of the passageway 11 on the other side of the plug member 85.

From the plug member 85, the passageway 11 extends on through the handle 24 and intersects with the passageway 111 extending longitudinally through the body 22 of the gun 20. As previously discussed, a plug member 109 is mounted in the rear end portion of the passageway 111 to thereby effectively seal that end of the passageway.

The nozzles 28 and 29 of the nozzle head 26, which is mounted on the front face of the body 22 of the gun 20, include nipples 28c and 29c which extend rearwardly through, and are threadedly engaged in, tapped openings 30 and 32, respectively, in the nozzle plate 31, to thereby afford coupling members to which the hoses H1 and H2 may be connected. The forward end portions of the openings 30 and 32 are each countersunk to afford two enlarged channels 30a and 30b, and 32a and 32b, respectively, in the front face of the nozzle plate 31. As is best seen in Fig. 5, the nozzle bodies 28b and 29b include flanges 28d and 29d which are disposed forwardly of the nipples 28c and 29c, respectively, and, when the nozzle bodies 28b and 29b are disposed in operative position in the openings 30 and 32, the flanges 28d and 29d are disposed in the channels 30b and 32b in sealing relation over the front face of the recesses 30a and 32a, respectively. Thus it will be seen that inasmuch as the rear faces of the recesses 30a and 32a are sealed by the nipples 28c and 29c, respectively, the recesses or channels 30a and 32a afford annular passageways in the plate 26 around the respective nozzle bodies 28b and 29b when the latter are mounted in operative position in the openings 30 and 32.

A bifurcated passageway 115, having a main branch 115a and two smaller branches 115b and 115c, Fig. 5, is formed in the plate 26 with the main branch opening outwardly through the rear face of the plate in alignment with the front end of the passageway 111 in the body 22 of the gun, and with the two smaller branches 115b and 115c connecting the main branch 115a to the annular passageways 30a and 32a, respectively. Each of the nozzle bodies 28b and 29b have three openings 118a, 118b and 118c, and 119a, 119b and 119c, respectively, formed therein to afford passageways connecting the passageways 30a and 32a with the chambers 28g and 29g defined by the nozzle body 28b and the nozzle cap 28a, and the nozzle body 29b and the nozzle cap 29b, respectively, the passageways 118a-118c, and 119a-119c being spaced evenly around the longitudinal axis of the respective nozzle bodies. Each of the nozzle caps 28a and 29a has a discharge orifice 28e, 29e, respectively, formed in the central portion thereof disposed in alignment with the central passageways 28f and 29f in the nozzle bodies.

Thus it will be seen that air may be fed from the passageway 111 in the body 22 of the gun 20 into the main branch 115a of the passageway 115, from which it may be simultaneously evenly fed through the two nozzles 28 and 29. In so passing through the nozzles 28 and 29 it will be seen that part of the air flows from the branch 115a through the branch 115b, the passageway 30a, the passageways 118a-118c, the chamber 28g and out the orifice 28e, and the other portion flows from the branch 115a through the branch 115c, the passageway 32a, the passageways 119a-119c, the chamber 29g and out the orifice 29e.

The nozzle caps 28a and 29a are so disposed

on the nozzle bodies 28b and 29b, Fig. 5, that fluid, such as a silvering solution and a precipitating solution, may be drawn through the nozzle bodies 28b and 29b and discharged through the orifices 28e and 29e by the aspirating effect of air passing from the passageways 118a—118c and 119a—119c through the chambers 28g and 29g and out the orifices 28f and 29f.

Operation

For the purpose of illustrating the operation of the spray gun shown in Figs. 1 to 6, inclusive, the spray gun 20 is shown as used in silvering mirrors, wherein a silvering solution and a precipitating solution may be sprayed simultaneously from the gun onto the back of a sheet of glass, or mirror, such as the mirror M shown in Fig. 2. In such an operation, the glass or mirror to be silvered is normally disposed at an angle of approximately 60° to the horizontal, on a suitable supporting frame such as the frame F, Fig. 2. The silvering solution and the precipitating solution may be mounted in suitable reservoirs such as bottles A and B, respectively, and these bottles are normally mounted on the frame F at substantially the height of the top of the mirror M, or slightly above, and may be connected to the spray gun nozzles 28 and 29, respectively, by suitable feed lines such as hoses H1 and H2, Fig. 2.

Air may be fed to the gun 20 from a suitable source of supply, not shown, through a suitable conduit such as a combination filter and pressure regulating device D and a hose H3, the filter and pressure regulating device D having an inlet connection 135 which may be connected to the source of compressed air, and having an outlet connection 136 to which one end of the hose H3 may be connected, the other end of the hose being connected to the coupling member 46 mounted in the handle 24 of the gun 20.

With the gun 20 and other apparatus, arranged in the manner shown in Fig. 2, and with the lever 96 disposed in the position shown in Fig. 6, wherein the hoses H1 and H2 are open, it will be seen that the mirror M may be simultaneously coated with a silvering solution and a precipitating solution sprayed from the gun 20. In such an operation, the operator, while holding the handle 24 of the gun 20 in his hand, depresses the trigger 75 of the gun thereby unseating the valve 54 and permitting air to flow from the source of supply through the filter and pressure regulating device D, the hose H3, the coupling member 46, the passageway 40 in the handle 24, the valve housing 48, the passageway 71, the passageway 111, the branch 115a of the passageway 115, and then simultaneously through the branch 115b, the passageway 30a, the passageways 118a—118c, the chamber 28g, and the orifice 28e, and through the branch 115c, the passageway 32a, the passageways 119a—119c, the chamber 29g, and the orifice 29e. The aspirating effect of the air passing through the chambers 28g and 29g and the orifices 28e and 29e, causes the silvering solution and the precipitating solution to flow from the bottles A and B, respectively, through the hoses H1 and H2, the passageways 28f and 29f in the nozzle bodies 28b and 29b, and outwardly through the orifices 28e and 29e. The nozzles 28 and 29 are disposed at somewhat of an angle to each other so that the solutions thus sprayed therefrom converge a short distance forwardly thereof. I have found that

if the nozzles 28 and 29 are disposed on the base plate 26 in such a manner that each nozzle is set at an angle of substantially 4° toward the other nozzle, good silvering results may be obtained with the gun 20. While holding the trigger 75 depressed, the operator moves the gun 20 horizontally back and forth across the face of the mirror M, starting at the top thereof, and applies an even coating of the two solutions 10 simultaneously.

From the foregoing it will be seen that I have provided a novel spray gun which is adapted to simultaneously and evenly spray two solutions from separate nozzles, in a novel and expeditious manner.

Also, it will be seen that I have provided a novel gun wherein the hoses by which the working fluid is fed to the gun, are supported in a novel and expeditious manner thereon.

In addition, it will be seen that my novel gun embodies a novel nozzle head constituted and arranged in a novel and expeditious manner.

Furthermore, it will be seen that I have provided a novel gun which is practical and efficient in operation, is quickly and easily assembled and disassembled for the purposes of cleaning and repairing, and may be readily handled.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In a spray gun comprising a body member formed with an elongated passageway adapted to communicate with a passageway formed in a handle member mounted at and depending from the rear end portion of the body member, a plate member mounted on the front end of the body member and having a forwardly disposed face, said plate having two recesses disposed in spaced relation to each other in said forwardly disposed face, two elongated nozzle members mounted in said plate each comprising an elongated nozzle body projecting forwardly from said plate and also comprising a nipple element extending through an associated one of said recesses, each nipple element being adapted to be connected to a hose for conducting liquids and the rearward face of each nozzle body being disposed in sealing relation around the periphery of the associated recess, each nozzle body and nipple element having a passageway extending longitudinally therethrough for feeding liquid therethrough, said plate having passageways in communication with the passageway in the body member and each of the recesses for feeding air from the body passageway simultaneously to said recesses, each of said nozzle bodies having a plurality of passageways leading from the associated recess and opening at the front of the nozzle body, the said plurality of passageways being arranged concentrically about each of the said longitudinally extending passageways, the nozzle members being disposed in the plate in substantial parallel relation to the said body member, and manually adjustable clamp means mounted at the rear end of the body member adapted to regulate the flow of liquid through the hoses, the clamp means being aligned substantially with the nozzle members whereby the hoses may be disposed along the opposite sides of the body mem-

ber in parallel relation when attached to the nipple elements.

2. In a spray gun of the type embodying an elongated body member having a passageway extending from the rear end forwardly and opening at the front end, and a handle mounted on said rear end and having a passageway therein in communication with the passageway in the body member for feeding air out the said front end, a supporting plate mounted on the said front end and having a passageway in communication with the body passageway, the front face of the plate being formed with a pair of spaced apart and open front recesses each in communication with the plate passageway, a nozzle member mounted on said plate in association with each of the recesses and projecting forwardly of the plate, each nozzle member including a nipple element to which a hose may be attached, an elongated passageway extending through each nozzle member whereby liquids in the hoses may be sprayed from the forward ends of the nozzle members, each nozzle member including an annular flange disposed in sealing relation with respect to the open front of the associated recess in the plate, at least two passageways formed in each nozzle member on opposite sides of the said elongated passageway therein and leading from the associated recess to aspirate liquids sprayable from the front of the nozzles, the nozzle members being disposed in the plate in substantial parallel relation to the said body member, and manually adjustable clamp means mounted at the rear end of the body member, and being aligned substantially with the nozzle members whereby the hoses may be disposed along opposite sides of the body in parallel relation when attached to the nipple elements, the clamp means including a fixed element and an element movable relative to the fixed element whereby the flow of liquids in the hoses may be regulated when the hoses are disposed between the said fixed and movable elements.

3. In a spray gun of the type embodying an elongated body member having a front and rear end and having a passageway extending from said rear end forwardly through said front end, and a handle mounted on said rear end and having a passageway therein in communication with said passageway in said body member for feeding air into said first mentioned passageway, a supporting plate having parallel front and rear faces and being mounted on said body member with said rear face in engagement with said front end of said body member, said plate having a bifurcated passageway extending therethrough with the common end of said passageway opening through said rear face into communication with said passageway in said body member and each of the bifurcated ends of said passageway termi-

60

nating in a respective recess in said front face of said plate, two nozzle bodies mounted on said plate and projecting forwardly therefrom, each of said nozzle bodies comprising an elongated coupling member and an annular flange projecting laterally therefrom, each of said nozzles being disposed on said plate in a manner whereby said coupling members extend rearwardly and outwardly of said rear face of said plate, said flanges being disposed in sealing engagement with said front face of said plate adjacent the peripheral edge portions of said recesses to afford annular passageways around a portion of each of said coupling members, each of said nozzle bodies having an elongated passageway extending therethrough for feeding fluid forwardly through said coupling member thereof and discharging the fluid forwardly from said nozzle body, said elongated passageways in said nozzles being disposed in a forwardly converging angle relative to each other, two nozzle caps, each of said nozzle caps being mounted on the forwardly disposed portion of a respective one of said nozzle bodies and having a substantially conical shaped portion extending forwardly of said nozzle body in spaced relation thereto to afford a chamber therebetween, each of said nozzle caps having an orifice formed in said conical shaped portion forwardly of, and in alignment with, said passageway in said respective nozzle head, said orifice being in communication with the atmosphere and said chamber, each of said nozzles having a plurality of passageways therein in communication with said respective one of said recesses and said chamber to aspirate liquids dischargeable from said nozzles, and clamp means at the rear of the body member for clamping hoses connectable to the ends of the coupling members projecting rearwardly of the plate, the clamp means being aligned with the coupling members and the coupling members being aligned horizontally with the body member whereby the hoses may be disposed along the sides of the body member in parallel relation, the clamp means including elements for regulating the flow of liquid in the hoses.
